C. H. STRUPE

BANJO

Filed Oct. 28, 1925

Fig. 1.

Fig. 2.

UNITED STATES PATENT OFFICE.

CECIL H. STRUPE, OF INDIANAPOLIS, INDIANA, ASSIGNOR TO LEEDY MANUFACTURING COMPANY, OF INDIANAPOLIS, INDIANA, A CORPORATION OF INDIANA.

BANJO.

Application filed October 28, 1925. Serial No. 65,319.

My invention relates to improvements in musical instruments of the banjo type and has for one of its objects to provide improved means for tensioning the head.

5 Another object of my invention is to improve musical instruments of the banjo type from the manufacturing standpoint.

For the purpose of disclosing my invention I have illustrated one embodiment there-

10 of in the accompanying drawings in which

Fig. 1 is a plan view of an instrument embodying my invention;

Fig. 2 is a side elevation;

15 Fig. 3 is a detail plan showing more particularly the construction of the tension hoop at the neck juncture;

Fig. 4 is a detail section taken on the line 4—4 of Fig. 3;

20 Fig. 5 is a section taken on the line 5—5 of Fig. 3;

Fig. 6 is a detail section taken on the line 6—6 of Fig. 5, and

Fig. 7 is a detail section showing the manner of securing the resonator in position.

25 In the structure illustrated I provide a cylindrical shell 1 the metal of which at its lower end is doubled upon itself to form an annular flange 2. The metal at the upper and lower edges of the shell is spun or rolled

30 over to form beads 3 and arranged within the shell, abutting against the shell and between the beads 3 I mount a wooden band 4.

The neck 5 is secured to the shell in the usual manner and the head 6, as is usual, is

35 wrapped at its edges on the flesh ring 7 exteriorly surrounding the shell 1. For tensioning the head 6, I provide a tensioning hoop 8 which at its lower edge is provided with an annular flange 9, and for decorative

40 purposes and to reduce weight this flange may be scalloped at its edges as at 10. This hoop 8 is subjected to considerable strain and in order to maintain its strength uniform throughout its circumference and at

45 the same time accommodate the jointure of the neck 5 with the shell, at the point where this jointure is made the metal of the hoop constituting the annular flange 9 is bent up at 11 to lie parallel with the face of the hoop 8. In this way clearance is given from the neck and at the same time the necessity

50 for notching the flange 9 is avoided whereby the strength of the hoop throughout its en-

tire circumference is maintained substantially equal.

55 The hoop is adjusted on the shell by means of tensioning rods each comprising a sleeve 12 internally screw threaded and adapted to pass upwardly through the flange 2. The sleeve at the point where it passes through the flange and the opening through which the sleeve is passed is irregular in shape so as to maintain the sleeve against turning. Co-operating with this sleeve is a threaded rod 13 which passes through the flange 9 60 and has its threaded end taking into the threaded socket of the sleeve. This rod is squared as at 14 to receive a wrench or turning instrument so that the rod may be turned for the purpose of increasing or decreasing 70 the tension on the head 6.

On the bottom of the shell I provide a 75 detachable resonator which comprises a convex wooden bottom 15 preferably greater in diameter than the shell and having a cylindrical portion 16 formed of metal and of sufficient size to telescope the bottom of the shell. This cylindrical portion flares at 17 into a skirt 18 having a bead 19 which is turned over the edge of the wooden bottom. 80 At suitable intervals the cylindrical portion is provided with bosses 20 through which screws 21 pass to make frictional engagement with the side of the shell for holding the resonator in position.

85 It will be noted that due to the fact that the squared portion 14 of the tensioning rod projects above the flange 9 of the tensioning hoop, the tension of the head 6 may be adjusted without disturbing any of the parts of 90 the instrument and without removing the resonator.

I claim as my invention:

1. A musical instrument of the banjo type comprising a metallic shell, the metal of 95 which is bent upon itself near its bottom to form an exterior annular flange, a head, a flesh ring to which the head is attached surrounding said shell, a tensioning hoop exteriorly surrounding said shell and bearing upon said flesh ring and having an annular flange substantially parallel with the flange on the shell, tension means comprising an internally threaded socket member extending 100 through the shell flange and a rotatable threaded rod extending through the hoop 105

flange and threading into the socket member, and means by which the rod may be rotated from above the flange.

2. A musical instrument of the banjo type comprising a shell having an annular flange near its bottom, a head, a flesh ring surrounding said shell and to which the head is attached, a tension hoop surrounding the shell and bearing upon said head and having an annular flange, said flange at the point where the neck of the instrument joins the shell being bent up to lie parallel with the hoop, and adjustable tension rods passing through said flanges.
- 15 3. A musical instrument of the banjo type comprising a metal shell, the metal of which is doubled upon itself to form near the bot-

tom of the shell an annular flange, a head, a flesh ring to which said head is attached surrounding said shell, a tension hoop surrounding said shell and bearing on said flesh ring and having an annular flange, adjustable tension rods connecting said flanges and adjusted from above the flange on the tension hoop and a resonator comprising a wooden convex bottom of greater diameter than the shell and a cylindrical portion of smaller diameter and telescoping the shell, said cylindrical portion having a flaring skirt embracing at its lower edge the wooden bottom. 20 25 30

In witness whereof, I, CECIL H. STRUPE, have hereunto set my hand at Indianapolis, Indiana.

CECIL H. STRUPE.
